H. BARKSCHAT

CAPITAL CONSTRUCTION

Filed April 8, 1926

Inventor
Henry Barkschat

Attorney.

UNITED STATES PATENT OFFICE.

HENRY BARKSCHAT, OF LOS ANGELES, CALIFORNIA, ASSIGNOR TO MARBELITE CORPORATION OF AMERICA, OF LOS ANGELES, CALIFORNIA, A CORPORATION OF DELAWARE.

CAPITAL CONSTRUCTION.

Application filed April 8, 1926. Serial No. 100,769.

This invention has to do generally with structural characteristics of capitals such as are used in connection with ornamental lighting standards and the like, and is more particularly concerned with capitals which are made up of a main body member and separable elements.

In its broader aspects, the invention applies to means for joining these members and elements irrespective of the nature of the latter, that is, they may either be lighting fixtures attached directly to the capital or they may be made up of one or more ornamental members interposed between the capital body portion and lighting fixtures. Or the separable elements may be merely ornamental in nature, but having such characteristics that it is a matter of difficulty to mold them integrally with the body member.

For the purpose of illustrating a typical embodiment of my invention, I have shown a capital made up of a main body member having detachable pendant elements and detachable pedestals, the pedestals being in alinement with the pendants, but on top the capitals, and being adapted to support lighting fixture. However, by thus confining the drawings and description to these particularities of construction, and further showing and describing the capital and its separable elements as being made of concrete, I do not wish to infer that my broader claims are limited thereto.

In my co-pending application entitled Lamp post structure, Serial No. 11,054, filed Feb. 24, 1925, and finally allowed September 14, 1925, I have shown a junction box set in the body member of the capital, and from this junction box extend curved conduits. These conduits project vertically above the capital top and serve as means for making connection between the capital body and fixture supporting blocks. The curved conduit and junction box there shown are cast within the main body member of the capital, and therefore the conduit may not be detached from the box once the concrete has set, particularly in view of curvature of the conduit. In contradistinction to such a structure, I have here shown and have specified in certain of my broader claims, a junction box which is in alignment with the fixture supporting block so straight sections of

conduit may be used for connecting the body member and block, the conduit being capable of being connected to or disconnected from the box after the latter is set in the body member.

The general object of the invention is to provide means whereby separable capital elements may be quickly and rigidly attached to the main body portion of the capital. This is a feature of a great practical importance, for the capitals are ordinarily of considerable bulk and weight, and as a consequence, in erecting lamp standards, it is customary first to set the shaft portion of the standard, and then hoist the capital to its position on top of the shaft. Were the capitals to be made in one piece or to be made of separable units having such a type of connection as would require shop assembly, it would be a matter of great difficulty fully to erect a standard, and there would be every likelihood of damage to projecting or relatively delicate parts of the capital during erection. By virtue of the simple assembly provision herein shown, it is a matter of comparative ease to mount the body portion of the capital on the shaft and then independently attach the separable units or element, even though the workman be supported by ladder or scaffolding.

Other objects and novel features of the invention will be better understood from the following detailed description, reference being made to the accompanying drawings, in which:

Fig. 1 is a medial sectional view, partially in elevation, showing a structure embodying my invention;

Fig. 2 is an enlarged, fragmentary detail of one of the junction boxes and associated members, the stippling which represents concrete being omitted in order to avoid confusion; and

Fig. 3 is a fragmentary view showing a variational form of pendant attachment.

In the drawings the numeral 10 designates the upper part of a hollow, concrete shaft, though it will be understood the present invention is not limited to a supporting shaft of any particular nature.

Numeral 11 designates generally the main or body member of capital C, preferably of concrete, this body portion including neck 12, and lateral cross arms 13. Set, and pref-

erably cast centrally in body portion 11, is a metal junction box 14, the interior of which is accessible from the outside of the capital. This junction box, in addition to serving the purpose of allowing the distribution of wires W to the lighting fixtures, also provides means whereby body portion 11 is secured to shaft 10. The method of this securing is not essential to the present invention, but I have shown securing means similar to that described and claimed in the aforementioned, co-pending application. This means may be briefly described as a barrier or lock plate 15 extending across bore 16 of shaft 10, and a tubular tension rod 17 which extends into box 14 at 18 and has at its lower end a locking head 19 adapted to engage beneath plate 15. Nuts 20 are threaded on rod 17 where it extends within box 14, and holds the body member to the shaft.

Set in arms 13 near their extremities are junction boxes 21, the interior 22 of each box communicating with the interior of box 14 through conduit 23, nuts 24 being threaded on the conduit at opposite sides of the opposed walls of boxes 14 and 21 to hold the boxes in predetermined relation during the casting of the body portion.

The upper ends of boxes 21 open to the upper faces of arms 13 and are preferably closed by removable caps or plates 25 after wires W have been drawn from the bore of shaft 10 through tubular tension rod 17, junction box 14, conduit 23, and into the interiors 22 of boxes 21. Caps 25 have a central, threaded bore 26, and may be detachably secured to flanges 27 of boxes 21 by bolts 28. A tubular rod 29 is threaded into bore 26, and serves as a conduit for wires W which are drawn upwardly through said rod. Separable capital member or pedestal 30 has a bore 31 which is adapted to take rod 29, the pedestal having a counter-bored base portion 32 which covers box cap 25. Nut 33 is threaded down on rod 29 into engagement with the upwardly facing shoulder 34, provided at the bottom of pedestal bore 35, holding the pedestal against displacement with respect to cross arm 13. Lighting fixture support 36 is bolted at 37 to the upper end of pedestal 30, wires W extending to compensator P, which is suspended from support 36. Lamp socket S, lamp L and globe G are supported by member 36 in the customary manner.

It will be seen that cap 25 is, in effect, a plate set in body portion 11, and that by virtue of its threaded bore, and the fact that said bore opens into the interior of the box, rod 29 may be threaded longitudinally into the interior of the box, there being no necessity for limiting the longitudinal thread engaging movement of the rod, within reasonable limits. This is in contradistinction

to the type of solid barrier plate cast within a solid body member, where, unless there be provided a cored out portion below the threaded bore, the attachment rod can only be threaded through the plate and not therebeyond, thus necessitating certain limitations and niceties of construction which are to be avoided as far as possible, as will be readily understood. The box 21, and hence plate or cover 25, is held against rotation within member 11, both by reason of being cast in the body member and by reason of its attachment to box 14 by conduit 23.

The use of a box-like securing means is advantageous also for the reason that it provides unitary means for attaching a plurality of separable members to the body member, and that the rods extending from said separable members to the box may be in axial alinement and yet movable through the box towards and away from each other in the directions of their axes.

Thus, I have shown a separable member in the form of an ornamental, concrete pendant 38, the pendant, box 21 and pedestal 30 preferably, though not necessarily, being in axial alinement. Pendant 38 has a bore 39 extending longitudinally therethrough, the bore being adapted to take attachment rod 40. Rod 40 is passed up through bore 41 in arm 13 and its end 40^a is adapted to be threaded into bore 42 provided in the bottom wall or plate 43 of box 21, bore 42 preferably, though not necessarily, being in axial alinement with bore 26 in the spaced and oppositely disposed plate 25.

A nut 44, preferably of metal and of an ornamental nature, is adapted to be threaded on the lower end 40^b of rod 40, the nut holding the pendant with its upper end in engagement with the lower face of arm 13, or, expressed otherwise, holding the pendant against movement longitudinally along the rod in one direction.

In Fig. 3 I have shown a variational pendant construction, wherein attachment rod 40^c is cast within pendant, 38^a, the upper threaded extremity 40^c of the rod being adapted to be engaged threadably with bottom plate 43 of box 21 by rotation of the entire pendant. This construction eliminates the necessity of providing a retention nut such as 44 in Fig. 1.

Numeral 50 designates an ornamental separable member through which extends attachment rod 51, the lower, threaded end 52 of this rod being passed through a bore in top wall 53 of box 14, and being provided with a retention nut 54 below this wall. Rod 51 carries a sleeve nut 55 at its upper end, and a capping, ornamental member 56, has cast therein a bolt 57, the bolt being adapted to be threaded into sleeve 55, to hold members 50 and 56 in assembly on body member 11.

It will be noted that each of the attachment rods mentioned above is detachably connected to the particular box it enters, in contradistinction to the curved conduit shown in the aforementioned co-pending application which conduit, serving as connecting members between the main body and pedestal members, cannot be disconnected from their associated junction boxes.

10 It will be understood the drawings and description are to be considered merely as illustrative of and not restrictive on the broader claims appended hereto for various changes in design, structure and arrangement may be made without departing from the spirit and scope of said claims.

I claim:

1. In a post capital embodying a body member and a separable member, means detachably connecting the members and including a box set in the body member, and a rod extending at one end into the separable member and extending at its other end into a bore provided through one of the box walls 25 and being detachably connected to the box.

2. In a post capital embodying a body member and a separable member, means detachably connecting the members and including a plate set in the body member, a rod extending through the separable member and into detachable connection at one 30 end with the plate, and detachable means near the other end of the rod and adapted to hold the separable member against movement longitudinally along the rod away 35 from the body member.

3. In a post capital embodying a body member and a separable pendant member, means detachably connecting the members 40 and including a plate set in the body member and held against rotation with respect thereto, a vertical rod in the pendant and detachably secured to the plate, and detachable means near the other end of the rod 45 adapted to hold the pendant against move-

ment longitudinally along the rod away from the body member.

4. In a post capital embodying a body member and a pair of separable members arranged one above and one below the body member, means adapted to hold the members detachably together and including a box set in the body member, and a rod in each of the separable members, said rods being detachably connected to opposite walls of the box. 55

5. In a post capital embodying a body member and a pair of separable members arranged one above and one below the body member, means adapted to hold the members detachably together and including a box set in the body member, and a rod in each 60 of the separable members, said rods being threaded into bores provided through opposite walls of the box.

6. In a post capital embodying a body member and a pair of separable members arranged one above and one below the body member, means adapted to hold the members detachably together and including a box set in the body member, a removable cap for said 70 box, a rod in each of the separable members, one of said rods being tubular and being threaded into a bore provided through said cap whereby the bore of said one rod is in communication with the interior of the box, and a rod in the other separable member and threaded connected to another wall of the box. 75

7. In a post capital embodying a body member and a separable member, means detachably connecting the members and including a junction box set in the body member, a removable cap for the box, and a tubular rod in the separable member and detachably connected to the cap, the rod bore 80 communicating with the interior of the box. 85

In witness that I claim the foregoing I have hereunto subscribed my name this 26th day of March 1926.

HENRY BARKSCHAT.
